UNITED STATES PATENT OFFICE

FRED C. TAMS, OF CHICAGO, ILLINOIS, ASSIGNOR TO GLOBE SPECIALTY COMPANY, OF CHICAGO, ILLINOIS, A CORPORATION OF ILLINOIS

DESIGN FOR A CIGAR LIGHTER OR SIMILAR ARTICLE

Application filed December 7, 1931. Serial No. 41,985. Term of patent 7 years.

To all whom it may concern:

Be it known that I, FRED C. TAMS, a citizen of the United States, residing at Chicago, in the county of Cook and State of Illinois, have invented a new, original, and ornamental Design for a Cigar Lighter or Similar Article, of which the following is a specification, reference being had to the accompanying drawings, forming a part thereof.

Fig. 1 is a plan view of a cigar lighter or similar article showing my new design; and

Fig. 2 is an elevation of the cigar lighter or similar article shown in Fig. 1.

I claim:

The ornamental design for a cigar lighter or similar article as shown.

FRED C. TAMS.
